UNITED STATES PATENT OFFICE

FRANK A. RUSSELL, OF TULSA, OKLAHOMA, ASSIGNOR TO UNIT LOCK COMPANY, OF TULSA, OKLAHOMA, A CORPORATION

PADLOCK

Application filed July 23, 1928; Serial No. 294,594.

The invention relates to padlocks of the sliding shackle type, and one object thereof is to provide a generally improved and simplified lock of this character in which novel provision is made for limiting the outward sliding of the shackle, the stop means being placed in position from the interior of the lock body during assemblage, whereas, ordinarily a rivet for this purpose is passed 10 through a specially drilled opening in the said body.

A further aim is to provide a new and improved relation of parts facilitating assembly and embodying novel dog or bolt releasing means for freeing the shackle.

Another aim is to provide novel obscured means for securing a lock cylinder in the lock body.

Yet another aim is the provision of unique 20 means for limiting insertion of a key into a rotatable barrel within the lock cylinder and for holding said barrel against withdrawal from said cylinder.

With the foregoing in view, the invention resides in the novel subject matter hereinafter described and claimed, the description being supplemented by the accompanying drawings.

Figs. 1 and 2 are vertical sectional views 30 partly in elevation illustrating the lock in locked and released positions, or opened and closed positions, respectively.

Fig. 3 is a vertical sectional view on the correspondingly numbered line of Fig. 1.

Fig. 4 is a horizontal sectional view on the correspondingly numbered line of Fig. 2.

Fig. 5 is a fragmentary elevation of the interior end of the shackle and its stop ring.

Fig. 6 is a bottom plan view of the shackle 40 stop ring.

Fig. 7 is a top plan view of the locking dogs, pinion and springs.

Fig. 8 is a fragmentary side elevation, partly in section, of the parts seen in Fig. 7.

Fig. 9 is a fragmentary vertical sectional view of the key stop.

In the drawings above briefly described, the numeral 7 designates an appropriate body formed of any desired metal. This body is provided with relatively long and

short longitudinal bores 8 and 9; to receive the ends 10 and 11, of a U-shaped shackle 12, said ends having notches 13 and 14, for co-action with bolts or dogs yet to be described.

The longer end 10 of the shackle 12, is provided with a tapering or conical portion 43 whose larger end is disposed toward the extremity of said shackle end 10, and between said tapered or conical portion 43 and said extremity, a continuous peripheral groove 53 is formed in the shackle end 10. Applicable to the portion 43 before engagement of the shackle with the lock body, is a split resilient ring 44 whose normal diameter is slightly greater than the upper end of the bore 8, and when the shackle end 10 is inserted in said bore, said ring 44 is somewhat contracted and passes through the upper end of this bore into an enlargement 42 of said bore. When the ring 44 has reached the enlargement 42, upon insertion of the shackle end 10, it expands under its own resiliency. Then, upon outward pulling of the shackle, the tapered portion 43 further expands the ring 44 and causes the latter to snap into the groove 53. The ring 44 is thus maintained in position upon the shackle end 10 to act as an effective stop to abut the upper end of the bore enlargement 42, thus preventing shackle 12 from being entirely withdrawn from the lock body 7. Whenever the shackle 12 is released, it is forced outwardly to the limit allowed by the stop ring 44, by means of a compression spring 26 which is disposed within a recess in the shackle end 10.

A lock cylinder 36 is secured in the central longitudinal recess 15 by a screw 37 which passes through an oblique opening 37' leading to said recess 15 from the inner end of the short bore 9. After insertion of this screw, a metal disk 49 is forced into the bore 9 to obscure said screw. Hence, an unauthorized person cannot remove the screw with the intention of later removing the cylinder 36.

A rotatable barrel 38 is disposed in the cylinder 36 and is controlled by a key 50. The upper end of this barrel projects beyond the cylinder 36 and is received in the lower end of an opening 32 which extends from the longitudinal recess 15 to the transverse recess 100.

16, said projecting end being provided with two driving studs 35. These studs straddle a driving rib 52 on the lower side of a cylindrical base 34 which is rotatably mounted in 5 the opening 32, said base being formed on a vertically elongated pinion 51. Turning of the barrel 38 by the key 50 causes the driving studs 35 and the rib 52 to rotate the base 34 and the pinion 51 for the purpose of 10 releasing the dogs 19, the inner sides of said dogs having opposed sets of teeth 19' which mesh with said pinion as seen most clearly in Fig. 7. The dogs are normally forced outwardly to operative position by appropriate 15 springs 20.

Formed in the barrel 38 is the usual keyway 50' which opens through the periphery of said barrel. In the inwardly projecting end of this barrel, a continuous peripheral 20 groove 54 is formed, said groove receiving a split resilient ring 48, a portion of the latter extending across said keyway 50', as seen in Fig. 9. This portion of the ring 48 constitutes a stop for limiting the insertion of the 25 key 50, and the portion of the ring projecting beyond the barrel 38, abuts the inner end of the cylinder 36, preventing withdrawal of said barrel from said cylinder.

By providing the novel construction shown 30 and described or the equivalent thereof, a lock is provided which may be easily and inexpensively manufactured, unusual speed being permitted when assembling. Moreover, the lock will be advantageous and exceptionally 35 durable, and its construction is such that it cannot be released by striking any part of the body with a hammer or other force. To open the lock the proper key must be inserted into the barrel 38 and the latter turned to 40 withdraw the dogs or bolts 19, whereupon the spring 26 expands and outwardly slides the shackle 12, which is stopped in its outward slide by the split stop ring 44. As excellent results are obtainable from the details 45 disclosed, they are preferably followed. However, within the scope of the invention as claimed, variations may be made.

I claim:

1. In a lock, a U-shaped shackle having 50 notches in the inner sides of its ends, a body having two longitudinal bores opening through one of its ends and slidably receiving said shackle ends, said body also having a central longitudinal recess which opens 55 through its other end, being further formed with a transverse recess from one of said bores to the other and having a cylindrical opening from the inner end of said longitudinal recess to said transverse recess, 60 spring-pressed bolts slideable in said transverse recess to engage said notches, said bolts having opposed sets of teeth at their inner ends, an elongated pinion between said sets of teeth and meshing therewith, said pinion 65 having a cylindrical base rotatably received

in said cylindrical opening, said cylindrical base and opening jointly forming means for rotatably mounting the pinion, a lock cylinder secured in said longitudinal recess and having a rotatable barrel, and separably interengaged driving means on the inner end of said barrel and said base of said pinion, said separably engaged means being separable upon withdrawal of said barrel. 70

2. In a lock, a body having a relatively deep longitudinal bore and a comparatively shallow longitudinal bore both opening through one of its ends, a longitudinal recess opening through its other end, and an oblique opening from the inner end of said shallow bore into the inner end of said recess, a shackle having one end pivotally and slidably mounted in said deep bore and its other end receivable in said shallow bore, locking means for said shackle embodying a cylinder in said recess, a screw passing through said oblique opening and threaded into said cylinder to secure the latter in place, and a disk secured in the inner end of said shallow bore and obscuring the head of said screw. 80

3. In a lock, a shackle, a body having a bore slidably receiving one end of said shackle, and a resilient split ring mounted on said shackle end and by its own inherent resiliency held in an expanded position at which it projects beyond the periphery of the shackle, forming a stop in said bore to limit the outward movement of the shackle. 95

4. In a lock, a body having a bore which is open at one end and enlarged inwardly of said end, a shackle having a straight end insertable into said bore, said shackle having a tapered portion whose larger end is disposed toward the extremity of said shackle end, said shackle end being provided also with a continuous peripheral groove between said tapered portion and its aforesaid extremity, and a split resilient ring applicable around the smaller end of said tapered portion and when so applied capable of contraction for passage through the smaller end of said bore into the bore enlargement, said ring being then adapted to expand within said bore enlargement, whereby outward pulling of the shackle will cause said tapered portion to further expand said ring and cause the latter to snap into said groove to constitute a stop for limiting the outward movement of the shackle. 105

In testimony whereof, I have hereunto affixed my signature.

FRANK A. RUSSELL.
